UNITED STATES PATENT OFFICE.

BARRON D. SOUTHARD, OF CHICAGO, ILLINOIS.

DESIGN FOR AN ELECTRIC-MOTOR FRAME.

SPECIFICATION forming part of Design No. 21,981, dated November 8, 1892.

Application filed June 20, 1892. Serial No. 437,383. Term of patent 7 years.

To all whom it may concern:

Be it known that I, BARRON D. SOUTHARD, a citizen of the United States of America, residing at Chicago, in the county of Cook and State of Illinois, have invented certain new and useful Improvements in Designs for Electric-Motor Frames, of which the following is a specification, reference being had to the accompanying drawings.

10 My design is illustrated in the drawings by means of two figures, of which Figure 1 is a side view of the frame, and Fig. 2 is an end view.

15 Looking at Fig. 1, the side portions of the frame are seen at A, having substantially-parallel adjacent surfaces a and swelling upon their opposite sides into the convex

portions a' . Between the parallel surfaces a is a cylindrical connection a^2 . From the portion a' the two sides curve toward each other ²⁰ and decrease in thickness, terminating at the top in concave surfaces a^4 a^5 , facing each other, and at the bottom in slightly-diverging portions a^3 , spreading slightly at the bottom. From each of the sides A extend lugs a^6 a^7 , ²⁵ the latter somewhat longer than the former.

I claim—

The design for an electric-motor frame, substantially as herein shown and described.

BARRON D. SOUTHARD.
